UNITED STATES PATENT OFFICE.

JOHN E. KALGREN, OF MINNEAPOLIS, MINNESOTA, ASSIGNOR TO THE J. R. CLARK COMPANY, OF MINNEAPOLIS, MINNESOTA, A CORPORATION OF MINNESOTA.

CLOTHES RACK.

Application filed July 29, 1925. Serial No. 46,780.

This invention provides an improvement in clothes racks and, generally stated, consists of the novel construction, combinations and arrangement of parts hereinafter described and defined in the claims.

In the accompanying drawings, which illustrate the invention, like characters indicate like parts throughout the several views.

Referring to the drawings:

10 Fig. 1 is a perspective view showing a clothes drying rack embodying the invention;

15 Fig. 2 is an enlarged fragmentary view partly in elevation and partly in section approximately on the line 2—2 of Fig. 1;

Fig. 3 is a plan view showing one of the split sleeves forming part of the invention;

20 Fig. 4 is an end elevation of the sleeve shown in Fig. 3; and

25 Fig. 5 is a plan view showing one end of one of the cross bars of the rack.

The clothes rack proper may take various different forms, but, as shown, it is made up of laterally spaced end bars 6, 7 and 8 and a plurality of cross bars 9 and 9^a connecting the corresponding end bars, as will hereinafter more fully appear.

30 The invention resides in the connection between the cross bars and end bars. The end bars are flat wooden members and the cross bars may be either round or angular in cross section, but, as shown, are rectangular and at their ends have turned-down round or cylindrical trunnions 10 formed

35 with centrally located grooves 11. Fig. 5 shows the normal form of the end portions of the cross bars. To pivotally connect the end bars, I provide split sleeves 12 preferably formed from stamped sheet metal and

40 provided with flanged ends 13 and in one side each with an inwardly pressed knob 14 that form unyielding approximately semi-spherical bosses. The said split sleeves 12 are passed through perforations in and pivotally connect the overlapped upper ends of the bars 8, the lower ends of the bars 8 to the upper ends of the bars 7, the intermediate portions of the bars 7 to the intermediate portions of the bars 6, the overlapped

50 upper ends of the bars 6—6 and the overlapped lower ends of the bars 7—7. In the lower portions of the bars 6 are also applied sleeves 12^a that are just like the sleeves 12, except that they are shorter, since they are

each passed through only one bar, while the sleeves 12 are each passed through two overlapped bars.

55 The trunnions 10 on the ends of the bars are arranged to be inserted into the axially aligned sleeves in the opposite end bars. More definitely stated, the trunnions 10 of the bars 9 are adapted to be forced into the axially aligned sleeves 12 that pivotally connect the end bars, while the lower bars 9^a are adapted to be forced into the shorter sleeves 12^a in the legs of the bars 6. In forcing the said trunnions into the cooperating sleeves, the inwardly pressed bosses 14 will cut or depress grooves 15 in the trunnions 10 leading from the outer ends of said trunnions to the grooves 11, and the said bosses then become seated in the grooves. When the bosses are seated in the grooves 11, there will be no danger of the cross bars becoming accidentally disconnected from the side 60 bars, but, nevertheless, if it should become desirable to remove any one of the cross bars to replace a broken cross bar, or for any other reason, this may be easily done simply by turning the cross bar so that its groove 65 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 70 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 75 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 80 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 85 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 90 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 95 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 100 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove 105 leading from the outer ends of the trunnions to the grooves 11, there will be no danger of the cross bars becoming accidentally disconnected from the side bars, but, nevertheless, if it should become desirable to remove any one of the cross bars to replace a broken cross bar, or for any other reason, this may be easily done simply by turning the cross bar so that its groove

aligns with the cooperating boss 14 and then pulling the said cross bar out of the cooperating sleeve. This provides a construction that permits the end bars to be pivotally connected at the factory and to be shipped in knockdown form with the cross bars disconnected and all of the parts of the rack compactly folded in very small space. Obviously, the rack may be quickly assembled after it has been shipped to its destination.

90 The bosses 14 are located midway between the ends of the sleeves and the grooves 11 are correspondingly located in the trunnion ends of the cross bars, and, hence, the trunnions of the cross bars can be forced into either end of the cooperating sleeves, and while the cross rods will not be positively interlocked to the sleeves when inserted therein, nevertheless, they will be held therein with sufficient security to prevent any accidental separation of the cross rods from the end members. By splitting the sleeves, they are made slightly expansible so that they will better adapt themselves to close frictional contact with the trunnion ends of the cross bars, even if said trunnion ends should vary somewhat in diameter.

What I claim is:

1. A clothes rack comprising end members each formed by a plurality of end bars, sleeves pivotally connecting the end bars, and cross bars having trunnion ends inserted into said sleeves, said sleeves having inwardly pressed approximately semi-spherical unyielding bosses and the trunnion ends of said cross bars having circumferential grooves into which the bosses of the cooperating sleeves are adapted to be forced. 20
- 5 2. A clothes rack comprising end members each formed by a plurality of end bars, sleeves pivotally connecting the end bars, and cross bars having trunnion ends inserted into said sleeves, said sleeves having inwardly pressed bosses and the trunnion ends of said cross bars having circumferential grooves into which the bosses of the cooperating sleeves are adapted to be forced. 25
- 10 15 3. A clothes rack comprising end members each formed by a plurality of end bars, sleeves pivotally connecting the end bars, and cross bars having trunnion ends inserted into either end of the cooperating sleeves. 30
- 30 35 In testimony whereof I affix my signature.

JOHN E. KALGREN.
